CULINARY DEVICE

Walter H. Rudolph, Brookline, Mass.

Application May 29, 1930, Serial No. 456,880

16 Claims. (Cl. 161—16)

This invention relates to egg cooking machines and particularly to machines of the type wherein an automatic timing device is incorporated for the purpose of insuring the cooking of the eggs for a predetermined length of time. The principal object of the invention is to provide a machine of the character set forth which will be of marked simplicity of operation. The setting of the timing device and the depressing of the carrier for the eggs to be cooked so as to submerge the eggs into the cooking compartment being affected by the manipulation of but a single manually operable member.

Another object of the invention is to provide a timing indicator or setting device on the top of the machine in a position such as to be clearly visible to the operator from any side of the machine.

A further object is to construct the main operating parts of the machine in the form of a self contained unitary structure capable of being attached to any suitable receptacle thereby obviating the necessity for the construction of a special tank equipped with slides and guide pieces such as characterize machines of this type as heretofore constructed.

Another object is to construct the principal operating parts as above set forth in standard units each of which is capable of being detachably secured to a suitable tank whereby machines of different capacity may be assembled merely by securing any desired number of units to the tank, thus enabling marked savings to be effected in the manufacturing cost as a result of standardization of the product.

A further object is to construct the units, hereinbefore referred to, in a manner such that a single source of power such as an electric motor or clock mechanism may be employed to operate any desired number of units.

Another object is to so construct the units, hereinbefore referred to, that the parts thereof can be made from standard gears, springs, tubing and cold rolled steel stock thereby eliminating as far as possible high production costs that would otherwise be involved if special castings, stampings or the like were employed.

A further object is to provide a machine of the character described in which not only the operating mechanism but the egg receptacle is readily removable from the cooking tank or compartment and in which the compartment is free from projecting parts so that it may be readily cleaned whenever desirable or necessary because of the breakage of any of the eggs and

the adherence to the sides of the compartment of the contents of the eggs.

Another object is to provide an egg cooking machine of attractive appearance, of compact, sturdy, and durable construction, of marked accuracy of timing, and in which the operating mechanism is effectively encased to prevent tarnishing or corrosion of the same, and of marked simplicity of construction and operation. And another object is to so construct the receptacle for the eggs that during the automatic raising of it out of the water in the cooking compartment, the rate of drainage of the water from the receptacle will be controlled so that said receptacle will perform the functions of a dash pot to prevent shock or jar to the eggs or operating mechanism.

The above and other objects of the invention will appear more fully from the following more detailed description and by reference to the accompanying drawings forming a part hereof wherein a satisfactory constructional example of a machine embodying the principles of the present invention has been selected for the purpose of illustration and wherein:

Fig. 1 is a rear elevation of an egg cooking machine embodying the principles of the invention;

Fig. 2 is a side elevation partly in section;

Fig. 3 is a plan view, partly in section, and partly broken away;

Fig. 4 is a central longitudinal section through one of the standard units including the operating mechanism;

Figs. 5 and 6 are sections on the lines 5—5 and 6—6 respectively of Fig. 4;

Fig. 7 is a sectional detail on line 7—7 of Fig. 6;

Fig. 8 is a detail, in perspective, of a latching lever;

Fig. 9 is a detail, in perspective, of a swinging lever for actuating the timing gears into and out of meshing relationship;

Fig. 10 is a detail, in side elevation, of a threaded sleeve or nut securing the operating knob or handle to the machine;

Figs. 11, 12 and 13 are details, in side elevation, of a plurality of telescoping members which forms a part of the means for setting and actuating the timing mechanism into the desired position.

As shown in Fig. 1 of the drawings, the invention contemplates the provision of standard units shown in elevation in Fig. 1, and designated generally by the reference character 10. In Fig. 1

of the drawings, two of such units are shown as secured to a tank, designated by the reference character 11. The unit at the left hand side of the figure is shown in elevated or inoperative position, while the unit at the right hand side is shown in depressed or operative position. The tank 11 may be of any suitable or desirable construction capable of containing a quantity of water in which the eggs to be cooked are submerged. This tank or the contents thereof may be heated electrically or by placing the same over a gas burner or other suitable heating device.

As shown most clearly in Figs. 2 and 4, each unit 10 includes a bracket 12 which projects into the tank 11 and carries an egg containing basket 13. The bracket 12 is suitably secured, as by means of the bolts 14, (Fig. 4), to the lower end of a vertically extending rod 15. This rod 15 is slidably mounted between a pair of guides 16, 17. The guide 17 is preferably formed integrally with a housing 18 which encases the timing gears and other actuating mechanism presently to be described. To the outer face of said housing is secured, as by the screws 19, a cover plate 20, (Fig. 1). This cover plate 20 is provided with a pair of apertures 21 arranged in axial alignment with a pair of screws 22 threaded into the back wall of the housing 18 and which, as shown in Figs. 2 and 4, are adapted to be clamped against the wall of the tank 11 to clamp the unit 10 securely in position upon said tank.

Mounted in an annular recess formed in the housing 18 and the guide 16 is an outer telescoping tubular casing consisting of the members 23, 24 and 25. The top of this casing is closed by a top plate 26 which, as shown in Fig. 3, is provided with suitable indicia 27 to indicate the different time intervals for which the machine is adapted to be set to secure a cooking of the eggs to the desired predetermined condition. Mounted for rotation above the plate 26, and in proper operative relationship to the indicia 27, is a pointer 28 which projects laterally from an annular plate 29. The plate 29 is clamped in position by a ferrule 30 in which is secured an actuating knob 31, or other suitable manipulating member, for setting the unit and actuating it as will hereinafter be described. Suitably secured within and projecting downwardly from the knob 31 is a small post 32 which preferably passes with a press fit into a threaded sleeve or nut 33. At its lower end the post 32 is bored and screw threaded for the reception of a headed screw 34 which serves to draw the ferrule 30 and knob 31, into clamped engagement with said sleeve 33. The sleeve 33, as clearly shown in Fig. 4, is threaded into a cooperating internally threaded sleeve or nut 35, the latter passing through an aperture in the top plate 26 and having an annular flange 36 which engages with the under side of said top plate. Interposed between the ferrule 30 of the knob 31 and the top plate 26, is a cup-shaped spacing sleeve 37 the edge of the annular flange of which engages the top face of the plate 26. When the knob 31 is secured to the nut 33 and the latter is screwed home into the internally threaded nut 35 with the spacing sleeve 37 placed upon the upper face of the plate 26, as shown in Fig. 4, the space between the opposed faces of the flange 36 and the flange of the sleeve 37 will be just sufficient to permit relative rotation between the knob 31, and the parts con-

nected thereto, and the plate 26, but will prevent any appreciable longitudinal movement of said knob relatively to said plate. The indicia 27 may be formed directly upon the plate 26, or may be provided upon a separate thin sheet 38, of any suitable material. As will be readily understood from an inspection of Fig. 4 the plate 29 which includes the indicating pointer 28, is also clamped in position relatively to the knob 31 by means of the nuts 33 and 35 and the spacing sleeve 37. The plate 26 is held against rotation by means of its connection to the post 15, said connection as shown consisting of a small knee shaped bracket 39 and screws 40, 41.

At its lower end, the nut 35 is provided with a depending annular flange 42 which defines a recess 43 having at its inner end a small annular groove 44. Seated within the recess 43 is a tubular telescoping member 45 having at its upper end a small projecting rib which is adapted to seat within the annular recess 44. The telescoping member 45 is provided with a pair of longitudinally extending diametrically opposed slots 46 which form keyways in which are slidably received a pair of laterally projecting lugs or keys 47 formed at the upper end of a second tubular member 48. The keyway slots 46 in the tubular member 45 permit the upper end of the member 45 to be sprung inwardly so that the small rib at the upper end thereof may be engaged within the annular recess 44 in the flange 42. After the tubular member 45 is seated within the flange 42, the parts are drilled for the reception of a transversely extending pin 49 which holds the parts in assembled position. At its lower end, the member 48 is provided with a pair of inwardly projecting lugs or keys 47a which, as shown in Fig. 4, are slidably engaged within a pair of diametrically opposed, longitudinally extending, keyways 50 formed in the lower-most member 51 of the telescoping parts 45, 48, 51. In order to prevent the disengagement of the member 48 from the member 51, the latter is provided near its upper end with a transversely extending pin 50a the ends of which project into the keyways 50 and are adapted to engage with the inwardly turned lugs 47a located at the lower end of the member 48. A hole 48a is provided in member 48 for insertion of the pin 50a, said pin being put in place after the assembling of the members 45, 48, 51.

The lowermost member 51 is in the form of a shaft the lower end of which projects into the housing 18 and passes slidably through a pair of axially aligned apertures formed in the vertically spaced thrust plates 52, 53. These thrust plates 52, 53 are formed integrally with a bracket 54, (see Figs. 5 and 6), which is screwed to the inner face of the cover plate 20 of the housing 18. Mounted between the thrust plates 52, 53 and slidably, but non-rotatably, associated with the lowermost telescoping member 51 is a spiral gear 55. This gear is in meshing engagement with a similar gear 56 keyed to a jack shaft 57. The jack shaft 57 has its ends journaled in suitable bearings provided in the bracket 54 and a second bracket 58, the latter also being secured to the cover plate 20. Keyed upon the shaft 57 is a disc 60 from the periphery of which projects a lug 61, (see Fig. 4 and 7). Rotatably mounted upon the shaft 57 is a spur gear 62 which is in mesh with a smaller spur pinion 63. The pinion 63 is rotatably mounted upon a stud 64 carried by the lower end of a swinging lever 65. At its upper end, 75

the lever 65 is rotatably mounted on the shaft 57. The stud 64, carried by the lower end of the swinging lever 65, has an extension in the form of a pin 64a, which passes into an elongated slot 66, formed in the upper end of a second swinging lever 67. At its lower end, the lever 67 is pivotally mounted upon a pivot shaft 68, mounted at its ends in the brackets 54, 58. The lever 65 is rotatably mounted on the shaft 57. The stud 64, carried by the lower end of the swinging lever 65, has an extension in the form of a pin 64a, which passes into an elongated slot 66, formed in the upper end of a second swinging lever 67. At its lower end, the lever 67 is pivotally mounted upon a pivot shaft 68, mounted at its ends in the brackets 54, 58.

The spur gear 63 is adapted to be brought into and out of mesh, in a manner presently to be described with a driving pinion 69. The latter is keyed to a main actuating shaft 70, which is suitably journaled in the brackets 54, 58, and is provided adjacent each end thereof with a transverse pin 70a adapted to be engaged within slots 70b of a connecting sleeve 70c by which the shaft 70 may be connected to the shaft 70 of an adjacent unit or to any suitable operating mechanism, such as a clockwork, or preferably a synchronous electric motor 71, such as illustrated, more or less diagrammatically in Fig. 1 of the drawings. Each end of the shaft 70 is provided with a pin 70a and each end of the sleeve with slots 70b.

The swinging lever 67, above referred to, has formed integrally with it an extension 67a, which terminates in a yoked end, (see Fig. 9) 67b, having a pair of inwardly extending lugs 67c, which project into an annular groove of a thrust collar 72, slidably mounted on the lower end of the lowermost telescoping member 51. The thrust collar 72 is prevented from moving off the end of the member 51 by means of a transverse pin 73. Mounted between the thrust collar 72, and a shoulder formed by reducing the lower end of the member 51, is a compression spring 74, the function of which will hereafter be described.

Projecting laterally from the side of the spur gear 62, hereinbefore described, is a pin 75, which is adapted to engage with a latch lever. The latch lever 76, as shown in perspective in Fig. 8 is provided, on its lower side with a lug 76a and at its inner end with a lateral extension 76d which terminates in a pair of apertured spaced ears 76b. Through the apertures of the ears 76b, and a pair of aligned apertures provided in the brackets 54, 58, pass pins 77 which serve to pivotally mount said lever 76 upon the sub-frame formed by the brackets 54, 58. Projecting upwardly from the lateral extension 76d of the lever 76 is a latch 76c. A spring 80 has its upper end suitably secured to the lever 76 to normally urge the latching lever 76 in a clockwise direction (Fig. 4) about its pivot pins 77, as well as to normally urge the sliding member 51 upwardly; the lower end of the spring 80 being secured to the rocker plate 80a pivoted on the pin 68 and engaging the lower end of the lower tubular member 51.

Mounted within the tubular casing formed by the telescoping casing members 23, 24, 25, is a compression spring 81 which at its lower end is fitted within the annular recess hereinbefore referred to and which is partly formed in the top of the housing 18, and also partly formed in the guide 16; the spring 81, at its upper end bears against the under face of the top plate 26.

The latch 76c of the latching lever 76 is adapted to engage with a collar 82 threaded onto the lower end of the upper telescopic member 45.

Mounted on the face of the spur gear 62 is a spiral spring 83, one end of which is secured to a pin, (not shown) projecting laterally from the spur gear 62, and the other end of which is se-

cured to a stationary pin, (not shown); the spring 83 functioning to cause the spur gear 62 to be normally urged in a clockwise direction. (Fig. 4), and to hold the pin 75 which projects laterally from the other side of the spur gear 62 in contacting engagement with the lug 61 upon the disc 60.

The manner in which the device operates is as follows:

Let it be assumed that it is desired to boil one or more eggs for 3½ minutes. The operator places the eggs in the basket or tray 13, which in the size machine illustrated has a capacity for 6 eggs. The knob 31 is rotated to bring the pointer 28 into alignment with the indication 3½ of the indicia 27. This rotation of the knob is communicated through the telescoping members 45, 48 and 51, (because of their keyed connection), to the spiral gear 55, thus rotating the said gear to an extent depending upon the extent of rotation given to the knob 31. The spiral gear 55 being in mesh with the spiral gear 56, the rotation is then communicated to the shaft 57 upon which the spiral gear 56 is keyed. As the shaft 57 is rotated it carries with it the disc 60 and a setting of the lug 61 which projects from the disc 60 is effected.

As the disc 60 and lug 61 are rotated in the manner just described, the coil spring 83 holds the pin 75 in contact with the lug 61; the pin 75, therefore, traveling in contact with the lug 61. The positions of the lug 61 and pin 75 shown in Fig. 4 of the drawings do not indicate the positions which these parts would occupy for a setting of the knob 31 at the 3½ graduation but the positions shown in the drawings correspond to a setting of the knob at the graduation 7; (this showing in Fig. 4 was adopted for clearness of illustration for had the pin and lug been shown in a position corresponding to the setting at the 3½ graduation the pin and lug would be obscured by the spiral gear 55.)

After the lug 61 and pin have been adjusted the operator then pushes downwardly upon the knob 31 thus causing the plate 26, the post 15, and bracket 12, to be depressed and the tray 13, with the eggs contained therein, to be submerged into the water contained within the tank 11. It will of course be understood that the water in the tank is heated to the boiling point by any suitable means as hereinbefore set forth. As the knob 31 and tray 13 move downwardly the telescoping casing members 23, 24 and 25 slide into one another and the downward movement just described is effected against the pressure of the spring 81. During the major part of the downward movement of the knob 31, the inner telescopic members 45, 48, 51 slide into one another until the pin 49 contacts with the upper end of the lowermost telescoping member 51. When this occurs, the member 51 is moved downwardly to a limited extent and this downward movement of the member 51 is communicated through the spring 74 to the thrust collar 72. During this limited movement, the engagement with the thrust collar 72 of the yoked inner and 67b of the swinging lever 67 causes the lever 67 to be swung upon its pivot 68 in a counter-clockwise direction. As the extension 64a of the stud 64 is engaged within the elongated slot 66 of the swinging lever 67, the swinging movement imparted to the lever 67 is communicated to the other swinging lever 65 which is, as hereinbefore described, mounted for swinging movement at its upper end upon the

60

65

70

75

80

shaft 57. The clockwise movement imparted to the lever 65 by the counter clockwise swinging of the lever 67 will cause the spur gear 63, carried by the lower end of the lever 65, to be moved 5 into mesh with the spur pinion 69 upon the main driving shaft 70. Assuming that the shaft is rotated by the synchronous motor 71, the driving effect will be communicated through the gears 69 and 63, to gear 62; the direction of rotation being such as to cause the gear 62 to be rotated in a counter-clockwise direction against the action of the spiral spring 83. The pin 75 will, therefore, travel away from the lug 61, and, after the lapse of 3½ minutes, according to the 10 assumed setting of the knob 31, will come into engagement with the lug 76a upon the latching lever 76. When the knob 31 has been depressed, as above described, to the lower-most limit of its travel, the collar 82 upon the lower end of 15 the upper telescopic member 45 engages under the latch 76c of the latching lever 76, the spring 80 causing the latch to snap over the collar 82 and hold the parts in their lowermost depressed 20 position.

25 The parts will be held in this lowermost position during the time required for the pin 75 to travel from its set position against the lug 61 until it engages the lug 76a of the latching lever. When this occurs the latching lever 76 will 30 be moved upon its pivot 77 in a counter-clockwise direction against the action of the spring 80. The latch 76c is therefore swung backwardly a sufficient distance to release the collar 82 and the parts are moved upwardly by the spring 35 81. Immediately upon the release of the latch 76c, and, as the pin 49 moves out of engagement with the top of the lowermost tubular member 51, the spring 80 will function through the rock- 40 er plate 80a to cause the member 51 and thrust collar 72 to move upwardly, thereby imparting a swinging to the lever 67 in a clockwise direction and thus moving the gear 63 out of mesh with the pinion 69. As the gear 63 is so moved out 45 of mesh with the pinion 69, the gear 62 will be free to move in a clockwise direction under the influence of the spiral spring 83 and the pin 75 will then be carried back to again contact with the lug 61; the backward clockwise movement of the gear 62 and pin 75 being stopped when the 50 latter engages with the lug 61.

Upon the release of the latch 76c from the collar 82 and the upward movement of the plate 26 by the spring 81 this upward movement is of course communicated through the post 15 and bracket 12 to the tray 13 thus causing the tray 55 to be elevated out of water. The tray 13 is preferably perforated to permit the water to drain through the bottom thereof but these perforations are so dimensioned that the water will 60 drain gradually from the tray 13 as the latter moves upwardly. At the beginning of its upward movement, the tray being entirely submerged, the spring 81 will have to overcome the weight of the tray, and of the eggs and water 65 therein, and the potential force of the spring when fully compressed can just overcome the weight to be lifted, the lifting movement therefore begins slowly. As the tray moves upward, the reduction in weight due to the drainage of 70 the water compensates for the reduced force of the spring as it extends, hence there will be no sudden jars or shocks. In this upward movement it will of course be understood that the inner telescopic members 45, 48, 51, as well as the 75 telescoping outer casing members, 23, 24, 25,

move to their fully extended position shown in Fig. 4.

As shown in the drawings the latching lever 76 is preferably extended through an elongated aperture or slot 85 in the cover plate 20 so that the latch 76c may be disengaged by a manual operation of the lever 76 if desired.

It will be seen from the foregoing description that any desired number of units may be detachably secured upon the side of any suitable tank or cooking vessel and, as but a very small amount of power is required to actuate the single train of gears of each unit that causes the movement of the pin 75 to disengage the latch 76c, a single synchronous motor may be employed to actuate 15 a plurality of units. The operation, however, of each unit is entirely independent of the other units, for example, one unit may be set for boiling eggs for two minutes while the unit immediately adjacent thereto may be set to boil eggs 20 for five minutes, without the difference in setting of one of the two units in anywise effecting the operation of the other.

It will be noted that the main operating parts located within the housing 18 are carried by the 25 sub-frame formed by the brackets 54, and 58, and, that, as said brackets are secured to the detachable cover plate 20, such parts may be readily removed for inspection or repair; this 30 constructional expedient also facilitates the assembling of the parts in the manufacture of the device.

It will also be noted that most of the parts of the mechanism may be readily constructed of standard stock gears, tubing, cold rolled stock 35 or the like, and that therefore the device may be manufactured at a comparatively low cost.

While I have shown a satisfactory constructional example that has proven successful in actual practice, it will be understood that the invention is not limited to the specific constructional details of the example selected for illustration, but that many changes, variations and modifications may be resorted to without departing from the principles of the invention. 45

While the invention has been described by way of example in connection with the boiling of eggs it will be understood that such example has been selected merely for convenience of description and that the device may be successfully 50 used for many different purposes where it is necessary or desirable to cause mechanical movement to take place after the desired predetermined period of time has elapsed.

I claim:

1. In an egg cooking machine of the type wherein an egg receptacle is adapted, by the actuation of a manually operable handle, to be submerged in a body of water in cooking vessel for time interval predetermined by the adjustment of a time controlled mechanism and to be automatically elevated out of said water at the expiration of said time interval, characterized by the provision of a single operating handle for depressing said receptacle and connections from said handle directly to said receptacle and additional connections from said handle to said time controlled mechanism for adjusting the latter by the manipulation of said handle to set said mechanism to vary said time interval, said time control mechanism and the connections to said handle being located exteriorly of said cooking vessel. 65
2. An egg cooking machine of the type wherein an egg receptacle is adapted to be submerged 70

2. An egg cooking machine of the type wherein an egg receptacle is adapted to be submerged 75

- in a body of water for a time interval predetermined by the adjustment of a time controlled mechanism and to be automatically elevated out of said water at the expiration of said time interval, characterized by an actuating gearing adapted to be driven from a shaft rotating at a substantially uniform angular velocity, said gearing including a rotary latch releasing member, and an adjustable stop for governing the extent of rotation of said latch releasing member, a manually operable handle and gearing connecting said handle with said stop for setting said stop in adjusted position.
3. In an egg cooking machine, a housing, a chronometrical mechanism including a releasable latching lever, a tripping device for said lever, an adjustable member for governing the extent of movement of said tripping device, a manually operable handle, means for rendering said mechanism active and inactive and connections between said handle and said means and between said handle and said adjustable member for actuating either said means or said member by manual operation of said handle.
4. In an egg cooking machine, a unitary structure adapted to be detachably mounted on a water container and comprising an egg receptacle mounted for movement into and out of the water in said container, means for normally holding said receptacle out of said water, a handle for moving said receptacle into the water, a motor driven time controlled gearing and means for disconnecting said gearing and motor when said receptacle is out of said water, and connections between said handle and said last named means for connecting said gearing and motor when said handle is actuated to cause said receptacle to be submerged in said water.
5. In an egg cooking machine, a unitary structure mounted upon a water container and comprising an egg receptacle mounted for movement into and out of the water in said container, a manually operable handle mounted for reciprocating and rotatable movement, time controlled gearing including an adjusting device adapted to be set to a plurality of positions for rendering said gearing inoperative after the elapse of a predetermined time interval in accordance with the setting of said device, and connections, between said receptacle and said adjusting device for causing the reciprocating movement of said handle to move said receptacle into and out of said water, and for causing the rotatable movement of said handle to set said adjusting device.
6. In an egg cooking machine, a unitary structure secured to a water containing tank, comprising an egg receptacle, a single operating handle, means connected with said handle and said receptacle to cause said handle when moved in one direction to submerge said receptacle in the water in said tank, a time controlled gearing and mechanism, operatively associated with said handle and gearing, for rendering said gearing operative after said handle in its movement in said one direction causes the egg receptacle to be submerged, resilient means for normally holding said receptacle out of said water, a latch for retaining said receptacle in said water against the action of said resilient means, an adjustable device associated with said gearing for releasing said latch and means actuated by movement in said handle in another direction for setting said adjustable device.
7. A culinary machine of the type that includes a receptacle adapted to be moved into a cooking vessel, means for automatically moving the receptacle out of said vessel at the end of a predetermined time interval and time controlled gearing including adjustable means for governing the length of said time interval, characterized by the provision of a single operating handle, connections therefrom to said receptacle for causing movement of said handle in one direction to move said receptacle into said vessel, means associated with said handle and gearing for causing said gearing to be rendered operative after a predetermined movement of said handle in said one direction, and means associated with said handle and adjustable means for setting the latter handle is moved in another direction.
8. In a culinary device, a unit adapted for use in conjunction with a cooking compartment and comprising a gear housing having a guideway secured thereto, a post slidably mounted in said guideway, a bracket carried by one end of said post, a receptacle detachably mounted on said bracket, a manually operable handle connected to the other end of said post, resilient means operatively associated with said handle for normally urging said bracket and receptacle outwardly of said compartment, time controlled gearing mounted in said gear housing, a plurality of telescopic control members connecting said gearing and handle, and a telescopic casing enclosing said post, said resilient means and said telescopic control members.
9. In a culinary device, a unit adapted to be secured to a cooking compartment and comprising a gear housing having a guideway secured thereto, a post slidably mounted in said guideway, a bracket carried by one end of said post, a receptacle detachably mounted on said bracket, a manually operable handle connected to the other end of said post, resilient means operatively associated with said handle for normally urging said bracket and receptacle outwardly of said compartment, time controlled gearing including an adjustable device, means for throwing said gearing into and out of operative condition and means connecting said handle with said adjustable device and said last named means for actuating them by manipulation of said handle.
10. In a culinary device, a unit adapted to be secured to a cooking compartment and comprising a gear housing having a guideway secured thereto, a post slidably mounted in said guideway, a bracket carried by one end of said post, a receptacle detachably mounted on said bracket, a manually operable handle connected to the other end of said post, resilient means operatively associated with said handle for normally urging said bracket and receptacle outwardly of said compartment, time controlled gearing including an adjustable device, means for placing said gearing into and out of operative condition, and means connecting said handle with said adjustable device and said last named means, including a plurality of telescopic members connected for relative longitudinal, but non-rotative, movement.
11. A timing device of the type wherein means for actuating a movable member are caused to function at the end of a predetermined time interval, comprising a main driving shaft and means for actuating it at an accurately controlled uniform angular velocity, a latch releasing member, gearing including an adjustable means between said main shaft and said member and a manually operable handle for setting said

means to different adjusted positions to vary said time interval and for placing said gearing in operative condition.

12. In a culinary device, a unit adapted to be secured to a cooking compartment, said unit comprising a receptacle movable into and out of said compartment, resilient means for normally holding said receptacle out of said compartment, a manually operable handle for actuating said receptacle against the action of said resilient means into said compartment, latching means for holding said receptacle in said compartment, a time controlled gearing, including a main driving shaft, and a releasing device for said latching means rotatable by said gearing into engagement with said latching means, adjustable means interposed in said gearing between said releasing device and said driving shaft, and connections between said adjustable means and said handle for varying the extent of rotation of said device.

13. In a culinary device, a unit adapted to be secured to a cooking compartment and comprising a receptacle movable into and out of said compartment, a main driving shaft and means for driving it at an accurately predetermined, uniform rate of speed, gearing connected with said driving shaft, resilient means for normally holding said receptacle in an inoperative position relatively to said compartment, a manually operable handle movable in one direction for moving said receptacle, against the action of said resilient means, into an operative position, a latching device for retaining said receptacle against movement by said resilient means after it has been moved to said operative position, means operatively associated with said handle and gearing for rendering said gearing operative only when said receptacle reaches said operative position, means actuated by said gearing for automatically releasing said latching device at the end of a predetermined time interval, an adjustable stop associated with said gearing and means connecting said stop and handle for setting said stop by movement of said handle in another direction for varying said time interval.

14. A culinary device of the type wherein a food receptacle is mounted for movement by actuation of a manually operable handle into a cooking compartment and is held therein by a latching device which is automatically released and the receptacle moved from said compartment after a predetermined time interval, characterized by a gear housing into which said latching device extends located to one side of said compartment and out of the path of fumes or steam issuing therefrom, a reduction gearing mounted within said housing, means for connecting said gearing to a chronometric motor, said gearing including a rotatable latch releasing member, an adjustable stop for engagement by said latch releasing member and connections between said handle and adjustable stop, for setting the latter at different angular distances from said member thereby to vary the amount of travel of said member.

15. A culinary device of the type wherein a food receptacle is mounted for movement by actuation of a manually operable handle into a cooking compartment and is held therein by a latching device which is automatically released and the receptacle moved from said compartment after a predetermined time interval, characterized by a gear housing, a reduction gearing mounted therein, including a main driving shaft, means for connecting said shaft to a chronometric driving motor, said gearing including means for releasing said latching device, means interposed between said releasing means and said driving shaft for connecting and disconnecting said gearing and connections from said manually operable handle to said last named means for operating the same by the actuation of said handle.

16. In a culinary device an unitary structure having means for detachably securing it to a cooking vessel and comprising a receptacle, a handle for moving said receptacle into said vessel, automatic means for moving said receptacle from said vessel at the end of a predetermined time interval, a telescoping housing connecting said receptacle and handle and located at one side and exteriorly of said vessel, a gear housing below said telescoping housing exteriorly of said vessel, time controlled gearing within said gear housing and connections from said handle to said gearing extending through said telescoping housing for adjusting said gearing to vary said time interval, said gearing and connections being completely enclosed within said housing and out of the path of steam, smoke or fumes from said cooking vessel.

WALTER H. RUDOLPH.

CERTIFICATE OF CORRECTION.

Patent No. 1,986,412.

January 1, 1935.

WALTER H. RUDOLPH.

It is hereby certified that error appears in the printed specification of the above numbered patent requiring correction as follows: Page 3, line 67, second column, for "and" read end; and page 5, second column, line 16, claim 7, after "latter" insert the words when said; and that the said Letters Patent should be read with these corrections therein that the same may conform to the record of the case in the Patent Office.

Signed and sealed this 19th day of February, A. D. 1935.

Leslie Frazer
